R. J. COFFEY

SPRAYER

Filed April 19, 1926

UNITED STATES PATENT OFFICE.

ROBERT J. COFFEY, OF OAKLAND, CALIFORNIA.

SPRAYER.

Application filed April 19, 1926. Serial No. 103,055.

This invention relates to improvements in sprayers for use in connection with the spraying of varnishes, lacquers, enamels and the like upon surfaces to be treated, such as the bodies and other parts of motor vehicles.

The general object of the invention is to provide a construction in sprayers adapted for use with various types of liquid varnishes, lacquers, enamels and the like, the fluid characteristics of which may differ one from the other.

The above and other objects are accomplished by instrumentalities pointed out in the following specification.

The invention is clearly defined in the claims.

A satisfactory embodiment of the invention is illustrated in the accompanying drawings forming part of the specification and in which

Figure 1 is a contracted vertical cross section taken through the tank of this invention and showing the spraying apparatus partly in section and partly in side elevation and arranged for use.

Figure 2 is a detail longitudinal section of the air nozzle, and

Figure 3 is a contracted longitudinal section of the fluid nozzle.

The tank 5 is of metal and of ordinary construction and of a size that may be conveniently held and supported by one hand of the operator. The upper end portion of the can is contracted to provide a neck 6 which is screw threaded so as to accommodate a screw threaded cap or closure 7 of ordinary construction. The lacquer, varnish or enamel 8 to be sprayed is poured into tank 5 from its original package or other container. The fluid outlet tube 9 extends into tank 8 through a fiber gasket 9' disposed in an opening in the top portion 10 of the tank, the tube being of a size to snugly fit within the gasket so that the tube may be adjusted vertically with respect to the position of the parts shown in Figure 1, and be frictionally held against accidental displacement in any of its adjusted positions.

11 is an outlet nozzle for fluid tube 9, and is arranged in the outer end portion of the tube and constructed so that the size of the passage therethrough may be varied. In the present instance I have shown the nozzle as being made up of two telescopic tubular

sections indicated respectively by 12 and 13, the larger section 12 being tightly fitted in the outer end portion of tube 9 and formed of metal. The smaller section 13 is also formed of metal, and telescopes into section 12, and its size is such as will permit of the parts 12 and 13 being held by friction against accidental displacement.

14 is an air tube that is adapted to be connected to an air pump of improved construction. For present purposes, the tube 14 can be regarded as being connected to an ordinary hand operated tire pump. 15 is an air nozzle insertable into tube 14. This nozzle is of metal and the tube is of rubber, and the size of the nozzle is such with respect to the cross sectional interior of tube 14 that when the nozzle is inserted into the tube as shown, the tube will be tensioned transversely, thereby operating to hold the nozzle against accidental displacement. 16 is an open-ended casing disposed transversely of the cap or closure 7 and fixedly secured thereto. This casing is preferably tapered longitudinally and is adapted to permit the nozzle to be inserted as shown and to frictionally bind on the nozzle 15, and thereby hold the same against accidental displacement. The nozzle 15 is by preference formed of three telescoping sections respectively indicated by 17, 18 and 19. These sections are frictionally held together the outer section being adjustable longitudinally of the intermediate section 18, and the latter being adjustable longitudinally of the section 17.

In the use of the device and when the parts are positioned as shown in Figure 1, a current of air directed transversely across the tube of section 13 by section 19 causes partial vacuum within tube 9, whereupon the air pressure within tank 5 causes the fluid to move upwardly through tube 9 and nozzle 11 and the air operates to divide the fluid into a finely divided spray and to direct the same outwardly and away from nozzle 11. In this connection, it will be observed that an air vent 20 is formed in the upper portion 10 of the tank so that the interior thereof is at all times in communication with the outside atmosphere. In that the section 19 of air nozzle 15 is adjustable longitudinally, it is evident that the texture of the spray may be varied, that is to say, a relatively coarse or dense spray may be had when the section 19 is relatively close

to the end of section 13, and the coarseness of the spray diminishes as the section 19 is adjusted farther away from the end of section 13. In connection with the fluid outlet tube 9, and fluid nozzle 11, it is to be noted that these structures lend themselves readily in spraying relatively thick and relatively thin fluids. In instances where the fluid to be sprayed is relatively thin, the parts are arranged as shown in Figure 1. In a case where relatively thick fluid is used, section 13 is removed and fluid tube 9 is adjusted so as to aline the end of section 12 with section 19. The passage through section 12, being of greater cross-sectional area than the passage through the section 13, allows the relatively thick fluid to move readily upward therethrough.

Although I have shown and described one embodiment of my invention, it is to be understood that the same is susceptible of various changes; and I reserve the right to employ such as may come within the scope of the appended claims.

I claim:

1. A sprayer comprising a liquid holding tank, a fluid outlet tube having an inlet end portion extending into the tank and adjustably mounted in said tank, a nozzle connected to the outlet end portion of the said tube, said nozzle comprising telescoping sections detachably connected together, and an air nozzle connected to the tank and disposed in angular relation to the fluid nozzle. 25

2. A sprayer comprising a liquid holding tank, a fluid outlet tube having an inlet end portion extending into the tank and adjustably mounted in said tank, a nozzle connected to the outlet end portion of the said tube, said nozzle comprising telescoping sections detachably connected together, and an air nozzle detachably connected to the top of the tank and including a plurality of telescoping sections detachably connected with each other and disposed in angular 30 40 45 relation to the fluid nozzle.

ROBERT J. COFFEY.
